UNITED STATES PATENT OFFICE

EARL PETTY, OF WINFIELD, KANSAS, ASSIGNOR TO THE DE LAVAL SEPARATOR COMPANY, OF NEW YORK, N. Y., A CORPORATION OF NEW JERSEY

PROCESS OF PURIFYING WAX DISTILLATES

Application filed August 24, 1921. Serial No. 495,079.

In the refining of crude oils, it is customary to distill off successively products of successively higher boiling points, such as naphtha, illuminating oil, gas oil, wax distillates, leaving as a residue a stock commonly known as cylinder oil stock. These wax distillates carry in solution more or less wax (or paraffin) of crystalline form. It is desirable or necessary to separate these wax distillates into 10 their constituents, namely: neutral oils and wax (paraffin). My process relates to the treatment of these wax distillates.

The wax distillate is usually cut into one stream, subjected to refrigeration in order 15 to solidify the wax, and then to press filtration to effect the separation of the oil from the wax. The pressed distillate is then run into reducing stills and cut into various neutral oils of different gravities, viscosities, 20 colors and fire tests.

These processes are essentially bulk processes and involve the use of large plants, the handling of a large amount of stock and the expenditure of considerable time, and moreover do not effect a thorough separation of 25 the constituents. Moreover, the final distillations to produce light, medium and heavy stock seriously impair the color.

By my process the treatment is a continuous one, involves the handling at any one time of a relatively small amount of stock, effects the separation and purification expeditiously, dispenses with the necessity of a large and expensive plant, secures a thorough separation, and avoids serious decolorization in the 30 final distilling process.

An understanding of the preferred mode of executing the process may be more readily arrived at by means of a description in connection with a diagram of a workable apparatus, such diagram being shown in the drawing.

It will be understood that the elements of the apparatus are all individually old and 45 that no claim is made herein even to any new order or arrangement of such old elements, it being understood that the process herein described is not dependent for its execution upon any particular apparatus.

50 The first step in the execution of my proc-

ess is the step of distilling off from the crude petroleum the various distillates. Instead of cutting the wax distillate stock into one stream, the stock is divided into light, medium and heavy wax distillate stocks; and an 55 important feature of my invention consists in not only such separate distillation of such heavy, medium and light wax distillates, but in their separate treatment, for reasons hereinafter specified.

After the distillation of the several wax distillates, each is diluted separately with naphtha. Inasmuch as each distillate may be treated in the same manner, the process hereinafter described may be assumed to be 65 applied to any one of them. It will, of course, be understood that the lighter the distillate, the smaller the proportion of a light petroleum product, such as naphtha, that need be added thereto. Thus, I prefer to add to 70 the light distillate about forty-five per cent of naphtha, to the medium distillate about fifty per cent of naphtha and to the heavy distillate about fifty-five per cent of naphtha.

The thus treated distillate is then run into 75 a continuous agitator 10 to which is continuously added sulphuric acid. From this agitator the precipitated acid sludge, containing tarry and asphaltic materials, is drawn off 80 either continuously or at intervals, while the treated distillate overflows into another tank 11, wherein it is washed with water. The washed acid-treated distillate is then conveyed to another tank 12, wherein it is subjected to treatment with an alkali, such as 85 caustic soda, to neutralize the acid and is then run through a tank 13, in which it is washed with water. Instead of applying the alkali treatment in the tank 12, the stock and the caustic soda solution may be forced 90 through a pack of excelsior, as more fully described in a patent issued to me July 8, 1924, No. 1,500,202.

The product now comprises an emulsion of oil stock and an alkaline solution. The 95 emulsion is broken by means of a centrifugal separator 14 and the soap and alkaline water separated from the oil stock, which is now free of tar and asphalt. The wax, naphtha and oil are, however, still in solution and the 100

stock contains objectionable coloring matter.

I have found it decidedly advantageous to first separate the wax from the oil and then treat each separately to remove the 5 coloring matter and any tarry or asphaltic material which may not have been removed in the prior acid, alkali, washing and centrifugal treatments, thereby effecting a decided economy over the reverse treatment, 10 first to decolorize and then to separate; although it will be understood that the latter modification is within the broader scope of my invention.

The distillate flowing from the centrifugal 15 separator is conveyed through any suitable chiller 15 in heat exchange relation with chilled oil that has been separated as herein-after described and wherein its temperature is materially reduced, and thence, through a 20 refrigerating tank or coil 16 in heat exchange relation with a refrigerating liquid, such as refrigerated brine, thereby reducing the distillate to a temperature low enough to throw substantially all the wax out of solution. 25 The maximum permissible temperature will vary with the proportion of naphtha that has been added to the distillate. 35° F. is about the maximum permissible temperature, while 20° F. is about as low as would be permitted by economical considerations. A temperature of about 25° F. is a recommended 30 temperature with an average addition of naphtha.

The chilled oil and precipitated wax are 35 then transferred to a centrifugal separator 17, wherein the oil is separated from the wax. It has been heretofore assumed that it is impossible, in a centrifugal separator, to centrifugally separate oil and solidified or 40 paraffin wax and at the same time effect a continuous outflow of the wax. I have found it quite practicable, if the diluted distillate is subjected to the acid, alkali and centrifugal treatments described, to refrigerate the distillate and then, by centrifugation to effect 45 a thorough separation of the two constituents; it being understood that the precipitated wax is not a solid in the sense of being absolutely non-flowing. While satisfactory 50 separation and separate discharge could probably not be effected in every high speed centrifugal separator, such as an ordinary cream separator, I have found that a centrifugal separator, of essentially the type set 55 forth in the Snyder Patent No. 1,283,343, dated October 29, 1918, will function efficiently. It will be understood, however, that the process is not limited to the use of any particular centrifugal separator and that other 60 centrifugal separators may be found to be not only operative, but satisfactory; mention being made of a specific type of separator in order that those skilled in the art may practice the process without the necessity of experimenting with different types of separa-

tors before obtaining a sufficiently satisfactory result. It is true that the disposal of the outflowing wax may present some difficulties, without special attention to the sludge covers to carry the wax from the bowl, in that there 70 is a tendency of the wax, which is by no means as free-flowing as the oil, to clog the discharge spouts of the receiving pans; but this difficulty, even if not remedied, does not render the separating process impracticable. 75 However, the objection has been entirely overcome by the provision of steam jackets applied to the receiving pan or its spouts, or both, against which the wax impinges upon its discharge from the separator bowl and 80 which serve to so far raise the temperature of the wax as to substantially increase its fluidity, facilitate its ready discharge from the spouts of the receiving pan, and avoid clogging. This part of the process, however, 85 is per se not my invention, it being set forth in an application filed August 24, 1921, by Cyrus Howard Hapgood, Serial No. 495,134. The wax-free oil, as it flows away from the separator 17 through the double pipe chiller 90 15, absorbs heat from the incoming distillate, as hereinbefore described.

Each of the separated constituents—the oil-free paraffin wax and the wax-free oil—is then 95 separately subjected to the following decolorizing treatment. Each of said constituents is run into a mixer 18, into which is simultaneously fed from two to ten per cent of a clarifying and decolorizing agent, such as fuller's earth. The thoroughly mixed product 100 is continuously fed into a preliminary clarifier, which may be a vacuum filter 19 of any known efficient type, or a basket centrifuge. The preliminary clarification removes the heavier color particles. The 105 filtered and partially clarified product is then fed into a centrifugal clarifier 20, which removes the lighter particles of coloring matter. The oil or wax (whichever may be treated) is now practically free of objectionable 110 coloring matter as well as tar and asphalt.

Most of the naphtha is carried off with the oil and is removed therefrom by distillation. Such distillation should be carried on 115 at as low a temperature as possible. Any distillation tends to more or less discolor the oil, and if the preceding clarification has been very thorough (as it is likely to be if my process is carefully carried out), it may be 120 desirable, if complete decolorization is desired, to refilter the oil through fuller's earth.

Some naphtha will be carried out with the wax, and it is desirable to subject the wax also to distillation with optional re- 125 clarification.

From what I have said with regard to the 130 discoloring effect of distillation, it is obvious that the separate treatment of the light, medium and heavy wax distillates, as above de-

scribed, removes the necessity for final distillation to separate the mixed distillates, thereby both simplifying the process and avoiding an otherwise inevitable serious impairment of color.

5 My process also has the advantage of effecting the recovery of the wax in crystalline form.

Having now fully described my invention, 10 what I claim and desire to protect by Letters Patent is:

1. The process of producing purified wax-free lubricating oils of different gravities, which comprises separately distilling from 15 the crude petroleum a plurality of wax distillates of different specific gravities and subjecting each distillate separately to the following treatment: diluting the stock with a light petroleum distillate, agitating the diluted stock with acid, removing the acid sludge, agitating the stock with an alkali, subjecting the resultant emulsion to centrifugal force and separately flowing off the stock and the soap and alkaline solution, and 25 then subjecting the diluted stock to a separating treatment and the wax-free oil to a decolorizing treatment: the separating treatment comprising chilling the stock to a temperature sufficiently low to precipitate the 30 wax and subjecting the resultant mixture to centrifugal force and separately flowing off the wax and the lighter products; and the decolorizing treatment comprising intimately mixing with the wax-free oil a clarifying 35 and decolorizing agent and subjecting the mixture to a preliminary treatment to remove the heavier part of said agent and coloring matter and to a centrifugal clarifying treatment to remove the lighter part of 40 said agent and coloring matter and finally distilling off the diluent.

2. The process of producing purified paraffin and wax-free lubricating oils of different gravities, which comprises separately distilling from the crude petroleum a plurality 45 of wax distillates of different specific gravities and subjecting each distillate separately to the following treatment: diluting the stock with a light petroleum distillate, agitating the diluted stock with acid, removing the acid sludge, agitating the stock with an alkali, subjecting the resultant emulsion to centrifugal force and separately flowing off the stock and the soap and alkaline solution, and 50 then chilling the diluted stock to a temperature sufficiently low to precipitate the wax, subjecting the resultant mixture to centrifugal force and separately flowing off the wax and the oil, and afterward subjecting each of the last named products to the following treatment: intimately admixing therewith a clarifying and decolorizing agent and subjecting the mixtures to a preliminary treatment to remove the heavier part of said 55 agent and coloring matter and to a centrifu-

gal clarifying treatment to remove the lighter part of said agent and coloring matter.

3. The process of producing refined wax and wax-free oil of different specific gravities from a mineral oil stock containing wax and hydrocarbons having higher and lower boiling points than the wax, which comprises 70 distilling off from said stock a plurality of wax distillate stocks of different specific gravities, and subjecting each distillate stock separately to a series of operations comprising dilution with a light petroleum distillate, successive agitation of the diluted stock with acid and alkali, centrifugally breaking the emulsion produced by the alkali treatment 75 and outflowing the diluted stock substantially free of soap, water and alkali, refrigerating the diluted stock, centrifugally separating the wax and the lighter constituents and separately flowing off the separated products, 80 and decolorizing each product separately.

4. The continuous process of producing purified paraffin wax from a mineral oil stock containing wax in solution which comprises subjecting a flowing stream of the stock to the 90 following operations: agitation with acid with withdrawal of acid sludge and overflow of the treated stock, agitation with alkali, subjecting the outflowing emulsion to centrifugal force and separately flowing off the 95 stock, refrigerating the outflowing stream of stock to precipitate the wax, subjecting the flowing mixture of wax and oil to centrifugal force and separately flowing off the wax, mixing and agitating the outflowing stream 100 of wax with a clarifying and decolorizing agent and subjecting the flowing mixture to a preliminary purifying treatment to remove heavier coloring matter and to a centrifugal clarifying treatment to remove lighter coloring 105 matter.

5. The process of producing wax-free oil of different specific gravities from a mineral oil stock containing wax and hydrocarbons having higher and lower boiling points than the wax, which comprises first distilling off 110 from said stock a plurality of wax distillates of different specific gravities and afterward subjecting each wax distillate separately to dilution with a light petroleum distillate and 115 agitation with acid and alkali, with separation of the water and soap, then refrigerating and centrifugally separating the oil and wax, and then decolorizing each wax-free oil and distilling off the diluent, thereby avoiding a final distillation of the wax-free oil to 120 separate the mixed distillates and the resultant impairment of color.

6. The process of producing refined wax and wax-free oil of different specific gravities 125 from a mineral oil stock containing wax and hydrocarbons having higher and lower boiling points than the wax, which comprises first successively distilling off from said stock a plurality of wax distillates of different 130

specific gravities and afterward subjecting each wax distillate separately to dilution with a light petroleum distillate and agitation with acid and alkali, with separation of the soap and water, then refrigerating and centrifugally separating the oil and wax, and then separately decolorizing the wax and wax-free oil.

In testimony of which invention, I have hereunto set my hand, at New York, on this 10 19th day of August, 1921.

EARL PETTY.
